DESIGN FOR A COMBINATION SURFACE AND TOOL GRINDER

Arthur E. Ringsrud, Minneapolis, Minn., as-
signer to Continental Machines, Inc., Minne-
apolis, Minn., a corporation of Minnesota

Application November 9, 1939, Serial No. 88,151

Term of patent 14 years

To all whom it may concern:

Be it known that I, Arthur E. Ringsrud, a citizen of the United States, residing at Minneapolis, in the county of Hennepin and State of Minnesota, have invented a new, original, and ornamental Design for a Combination Surface and Tool Grinder, of which the following is a specification, reference being had to the accompanying drawing, forming part thereof.

The figure is a perspective view showing the

front, top and one side of a combination surface and tool grinder embodying my new design.

The other side of the machine is substantially identical with that illustrated, and the back of the machine is substantially plain.

I claim:

The ornamental design for a combination surface and tool grinder, as shown and described.

ARTHUR E. RINGSRUD.
